OF ONE-THIRD TO SAMUEL M. WEST, OF BAXTER SPRINGS, KANSAS.

PUMP.

1,122,178.

Specification of Letters Patent. Patented Dec. 22, 1914.

Application filed March 21, 1914. Serial No. 826,298.

To all whom it may concern:

Be it known that we, ERNEST N. WARD and FREDERICK J. WARD, citizens of the United States, residing at Baxter Springs, 5 in the county of Cherokee and State of Kansas, have invented certain new and useful Improvements in Pumps, of which the following is a specification.

Our invention relates to pressure operated 10 pumping systems, of the general type that embody a partially or wholly submerged pumping barrel or shell with means to introduce pressure into the barrel and to exhaust the same therefrom, and has particular 15 reference to improvements in apparatus designed to control this introducing and exhausting of pressure to and from the barrel.

An important object of the invention is 20 to provide apparatus of the above mentioned character, whereby pressure, such as compressed air, will be introduced into the submerged barrel or shell and exhausted therefrom, at the proper interval, so that said barrel will be completely filled with 25 and emptied of the water or other fluid to be elevated.

A further object of the invention is to 30 provide apparatus of the above mentioned character, embodying adjustable means whereby the intervals at which the pressure is introduced into and exhausted from the submerged barrel, may be varied, as may be required under the particular conditions.

A further object of the invention is to 35 provide apparatus of the above mentioned character, which is wholly automatic in operation, strong, durable, and convenient in use.

Other objects and advantages of the invention will be apparent during the course 40 of the following description.

In the accompanying drawings forming 45 a part of this specification and in which like numerals are employed to designate like parts throughout the same, Figure 1 is a side elevation of apparatus embodying our invention, parts thereof being shown in section for the sake of illustration, and, Fig. 2 is a central longitudinal sectional view 50 through a submerged barrel, included in the apparatus.

In the drawings wherein for the purpose of illustration is shown a preferred embodiment of the invention, the numeral 5 55 designates a coupling, having connection at

its opposite ends with pipes 6 and 7. Connected with the pipe 7 through the medium of an elbow 8 is a pressure inlet pipe 9, having a valve structure 10 connected therein, preferably a balanced globe valve structure. 60 Connected with the pipe 6 through the medium of an elbow 11 is a pressure exhaust pipe 12, having a valve structure 13 connected in the same, preferably a balanced globe structure. These valve structures 10 and 13 are operated by valve stems 14 and 15 respectively, having their ends arranged between longitudinally spaced strips or bars 16, and connected therewith by bolts 17 or the like, as shown. It is thus seen that the 70 valve structures 10 and 13 are simultaneously operated, one being closed as the other is opened.

Connected with the pipes 9 and 12, preferably below and adjacent the valve structures 10 and 13, is a preferably horizontally arranged bar or support 18, having a preferably vertically swinging shifting lever 19, pivoted thereto, as shown at 20. This shifting lever is arranged between the strips or 80 bars 16, to swing longitudinally thereof, and is adapted to engage with the ends of the valve stems 14 and 15 or other elements carried by the strips 16, to effect a reciprocal movement of such strips. 85

The numeral 21 designates a bell-crank lever, as a whole, comprising a longitudinal arm 22 and a transverse arm 23, such bell-crank lever being connected with the bar 18 preferably by means of the bolt or pivot 20. 90 Connected with the free end of the transverse arm 23 is a suitably stiff retractile coil spring 24, the opposite end of which is connected with the upper or free end of the shifting lever 19, as shown. From the foregoing, it will be seen that when the longitudinal arm 22 of the bell-crank lever occupies its lowermost position, the transverse arm 23 thereof will be disposed upon the right of the pivot 20, whereby the 95 spring 24 will quickly swing the shifting lever 19 to the right, this movement of the shifting lever effecting a movement of the strips 16 in the same direction, said lever engaging a stop 25, preferably provided 100 with shock absorbing means 26. There are two of these stops, which are identical, the same being connected with the valve structures 10 and 13, as shown. When the longitudinal arm 22 is swung to its upper po- 105 110

sition, the transverse arm 23 is swung to the left of the pivot 20, as indicated upon Fig. 1, whereby the spring 24 quickly swings the shifting lever 19 to the left, for effecting a corresponding movement of the strips 16, the lever 19 engaging the stop 25, as is obvious.

Means are provided to swing the longitudinal arm 22 of the bell-crank lever 21 up and down in a substantially vertical plane, the same comprising a link 27, connected with the outer end of the longitudinal arm 22, as shown. This link has its upper end pivotally connected with a reciprocating carriage 28, mounted to slide longitudinally upon an upstanding or vertical cylinder or shell 29, as shown. Connected with this carriage 28 are upwardly extending rods 30, suitably connected with a cross head 31, which is rigidly connected with a piston-rod 32. This piston-rod is mounted to reciprocate within the cylinder 29 and operates through an aperture in the cap or head 33, closing the upper end thereof, as shown. This aperture is preferably formed larger in diameter than the piston rod 32 whereby air may freely pass into and out of the upper portion of the cylinder, to prevent the creation of vacuums in such upper portion. Connected with the lower end of the piston-rod 32 is a piston 34 mounted to reciprocate within the cylinder 29.

Connected with the lower end of the cylinder 29 is a T-coupling 35, the lower end of which is connected with and closed by a plug 36, connected with and closing one end of a T-coupling 37. This T-coupling is connected with a pipe 38, connected with the coupling 5 through the medium of an elbow 39. Connected with the T-coupling 35 and in communication therewith is a pipe 40, the opposite end of which is connected with the coupling 5 and in communication with the interior thereof. Connected in the pipe 40 is a check-valve 41, of any well known or preferred type, preferably a ball check-valve. This check valve permits the passage of compressed air in the direction indicated by the arrow but prevents the same from passing in a reverse direction. Arranged near the check valve 41 is a cut off valve 42, connected in the pipe 40, and adapted to be manually operated to regulate the passage of the air through the pipe 40. Connected with the pipe 40 by means of a T-coupling 43 is a by-pass pipe 44, having a check-valve 45 connected therein, of any well known or preferred type, preferably a ball check-valve, adapted to permit of the passage of air in the direction of the arrow, but to prevent the passage of the same in an opposite direction. Connected in the by-pass pipe 44 to one side of and near the valve 45 is a cut off valve 46, adapted to be manually operated for regulating the pas-

sage of the exhaust air through the by-pass pipe 44.

As more clearly shown in Fig. 2, the pipe 38 extends exteriorly of a building 47, within which the apparatus hereinabove described is preferably located. The pipe 38 is connected with the upper end of a submerged barrel 48, of any well known or preferred type, adapted to be arranged within a well, mine, or any place from which it is desired to pump water or other fluids. The barrel 48 is preferably vertically arranged, and the lower end thereof is closed by a bottom 50, having inlet openings 51, formed therethrough, adapted to be covered and uncovered by upwardly opening check-valves 52, as shown. Connected with the lower end of the barrel 48 is an outlet pipe 53, to extend to any desired point at which it is desired to discharge the water or other fluid. The outlet pipe 53 is provided near its connection with the barrel 48 with an upwardly opening check-valve 54, to prevent the return of the water or other fluid from the pipe 53 into the barrel.

The operation of the apparatus is as follows: Assuming that the different parts of the apparatus occupy the position shown in Fig. 1, the valve structure 10 will be open while the valve structure 13 will be closed. Compressed air will now pass through pipe 9, valve structure 10, pipe 7, coupling 5, elbow 39, pipe 38, and into the upper end of the barrel 48, to force the water or other fluid therefrom, the same passing outwardly through pipe 53. Some of this compressed air also passes from coupling 5 through pipe 40, the amount thus passing being regulated by adjusting the valve 42. From the pipe 40 the compressed air passes into the lower end of the cylinder 29, to elevate the piston 34 therein, at a desired rate of speed, which may be determined by adjusting the valve 42. This upward movement of the piston 34 moves the carriage 28 upwardly, which in turn swings the free end of the longitudinal arm 22 of the bell-crank lever upwardly. When the horizontal arm 22 of the bell-crank lever is moved to its uppermost position, the transverse arm 23 will be shifted to the left to assume a position upon the opposite side of the pivot 20. When this takes place, the spring 24 quickly swings the lever 19 to the left, for opening the valve structure 13 and closing the valve structure 10. This preferably takes place when all of the water has been expelled from the barrel 48. The valve structure 13 being now open, compressed air will exhaust from the upper end of the barrel 48, passing through pipe 38, elbow 39, coupling 5, elbow 11, valve structure 13 and through exhaust pipe 12 to the atmosphere. This exhausting of the air from the barrel permits of the water filling the same, preparatory to the next expelling

operation. The compressed air in the lower end of the cylinder 29 is also exhausting to the atmosphere, whereby the piston 34 will be lowered at a desired speed, it being understood that the piston 34 moves downwardly by gravity, due to its weight and the weight of the carriage and associated elements. Pressure now passes from the lower end of the cylinder 29 through coupling 35, the outer end of pipe 40, T-coupling 43, by-pass pipe 44, the inner end of the pipe 40, coupling 5, pipe 6, elbow 11, valve structure 18, and through exhaust pipe 12 to the atmosphere. It is obvious that the speed at which the piston 34 will descend is controlled by adjusting the valve 46. When the piston 34 moves downwardly sufficiently the longitudinal arm of the bell-crank lever is again moved downwardly, whereby the transverse arm 23 thereof will be disposed upon the right of the pivot 20, the spring 24 again suddenly swinging the shifting lever 19 to the right, to open the inlet valve 10 and close the outlet valve 13. This operation may be repeated indefinitely.

It is to be understood that the form of our invention herewith shown and described is to be taken as a preferred example of the same, and that various changes in the shape, size and arrangement of parts may be resorted to without departing from the spirit of the invention or the scope of the subjoined claims.

Having described our invention, we claim:

1. In apparatus of the character described, pressure supply and exhaust pipes, valve means connected therewith, means to operate the valve means, a pivoted lever adapted to operate said operating means, a pivoted crank adapted to be swung to positions upon opposite sides of the pivot of the lever, and yielding means permanently connecting the pivoted crank with the pivoted lever whereby the lever is swung in either direction by the crank and held in either active position by the same.

2. In apparatus of the character described, pressure supply and exhaust pipes, valve structures connected therewith, means to alternately open and close the valve structures, a pivoted lever adapted to swing longitudinally of the means to move the same, a pivoted crank arranged near the lever to be swung to positions upon opposite sides of the pivot of the lever, a retractile coil spring connecting the outer portions of the pivoted lever and pivoted crank, and means to swing the pivoted crank.

3. In apparatus of the character described, pressure inlet and exhaust pipes, valve structures connected therewith, means to simultaneously open one valve structure and close the other, a pivoted shifting lever engaging the valve operating means to move

the same, a pivoted crank adapted to be swung to assumed positions upon opposite sides of the pivot of the shifting lever, a retractile coil spring connected with the outer portion of the shifting lever and the outer portion of the pivoted crank, and pressure operated means to swing the crank in one direction.

4. In apparatus of the character described, pressure inlet and exhaust pipes, valve structures connected therewith, a reciprocatory element connecting the valve structures to open and close the same, a pivoted shifting lever slidably engaging the reciprocatory element to move the same in opposite directions, a pivoted bell-crank lever having a transverse arm adapted to be moved to occupy positions upon opposite sides of its pivot point, a retractile coil spring connecting the transverse arm and the pivoted shifting lever, and means to swing the bell-crank lever in one direction.

5. In apparatus of the character described, a conduit through which pressure is to be supplied, a pressure supply conduit connected with the first named conduit, an exhaust conduit connected with the first named conduit, valve structures connected with the pressure supply and exhaust conduits, means to open and close the valve structures, an upstanding cylinder having means of communication with the first named conduit, a piston mounted to reciprocate within the upstanding cylinder to move upwardly upon the introduction of pressure therein, and connecting means between the piston and the valve shifting means to operate the valve shifting means upon the upward movement of the piston.

6. In apparatus of the character described, a pump barrel, an operating conduit connected with the pump barrel, pressure supply and exhaust conduits connected with the operating conduit, valve structures connected with the pressure supply and exhaust conduits, a device connecting the valves of the valve structures whereby they are simultaneously operated, a pivoted lever to shift the device, an operating lever pivoted near the pivoted lever, operative connecting means between the pivoted lever and operating lever, an upstanding cylinder, a piston arranged therein and adapted to move upwardly upon the introduction of pressure into the cylinder, connecting means between the piston and the operating lever, and a conduit establishing communication between the cylinder and the operating conduit.

7. In apparatus of the character described, a pump barrel, an operating conduit connected therewith, a valve structure for controlling the passage of pressure into the operating conduit, a plurality of pivoted levers, a spring connecting the levers, oper-

ative connecting means between one pivoted lever and the valve structure, a cylinder, a piston mounted to reciprocate therein, connecting means between the piston and one of the levers, and a conduit establishing communication between the cylinder and the operating conduit.

8. In apparatus of the character described, a pump barrel, an operating conduit connected therewith, a valve structure for controlling the passage of pressure into the conduit, means including a swinging lever to operate the valve structure, an operating lever pivoted near the swinging lever, a tractile coil spring connecting the ends of the levers, an upstanding cylinder, a piston mounted therein and adapted to move upwardly upon the introduction of pressure into the cylinder, connecting means between the piston and the operating lever, and a conduit establishing communication between the cylinder and the operating conduit.

9. In apparatus of the character described, the combination with a pump barrel, of a conduit to supply pressure to the pump barrel, an upstanding cylinder connected with the pressure supply pipe to receive pressure therefrom, a weight piston mounted to reciprocate within the cylinder and to be moved upwardly by pressure therein, and means operated by the piston when the same has moved upwardly for a predetermined distance to cut off the supply of pressure in the conduit.

10. In apparatus of the character described, the combination with a conduit, adapted to be connected with a pump barrel, of a pressure supply conduit connected with the first named conduit, an exhaust conduit connected with the first named conduit, valve structures connected with the pressure supply and exhaust conduits, an upstanding cylinder, a pipe connecting the cylinder and the first named conduit, a check-valve connected in the pipe, a by-pass pipe connected with said pipe upon opposite sides of the check-valve, a check-valve connected in the by-pass pipe, a piston mounted within the upstanding cylinder, and means for operating the valve structures having connection with the piston to be moved

thereby when the piston is moved in either direction.

11. In apparatus of the character described, a common conduit, a pressure supply conduit connected therewith, an exhaust conduit connected with the common conduit, valve structures connected with the supply and exhaust conduits, means to operate the valve structures, an upstanding cylinder, a gravity returned piston mounted within the cylinder, inlet and outlet check-valve control conduits connecting the cylinder and common conduit, and operative connecting means between the piston and the valve operating means.

12. In apparatus of the character described, a common conduit, a pressure supply conduit connected therewith, an exhaust conduit connected with the common conduit, valve structures connected with the supply and exhaust conduits, means to operate the valve structures, an upstanding cylinder, a gravity returned piston mounted in the cylinder, inlet and outlet conduits connecting the cylinder and common conduit, a check-valve connected in the inlet conduit, an oppositely opening check-valve connected in the outlet conduit, and adjustable means to control the passage of fluid through the check-valve controlled conduits.

13. In apparatus of the character described, a conduit provided with pressure inlet and exhaust means, means to operate the inlet and exhaust means, a shell, a movable pressure operated element connected therewith to be shifted by pressure therein, operative connecting means between the first named means and the movable pressure operated element, and a plurality of check-valve controlled conduits connecting the shell with the first named conduit, the check-valves opening in opposite directions with relation to each other, substantially as described.

In testimony whereof we affix our signatures in presence of two witnesses.
